UNITED STATES PATENT OFFICE

112,069

DESIGN FOR A BICYCLE

Horace M. Huffman, Jr., and John H. Horstman, Dayton, Ohio, assignors to The Huffman Manufacturing Company, Dayton, Ohio, a corporation of Ohio

Application August 14, 1937, Serial No. 71,101

Term of patent 7 years

To all whom it may concern:

Be it known that we, Horace M. Huffman, Jr., and John H. Horstman, both citizens of the United States of America and residing at Dayton, in the county of Montgomery and State of Ohio, have invented a new, original, and ornamental Design for a Bicycle, of which the following is a specification, reference being had to the accompanying drawings, forming a part thereof, and in which:

Fig. 1 is a side elevational view of a bicycle showing our new design, the dominant feature of the design residing in the part shown in full lines.

Fig. 2 is a top plan view of the tank alone;
Fig. 3 is a side elevational view of the tank;
Fig. 4 is a vertical sectional view through the tank on the line 4—4 of Fig. 3; and

Fig. 5 is a vertical sectional view through the tank on the line 5—5 of Fig. 3.

We claim:

The ornamental design for a bicycle, substantially as shown and described.
